UNITED STATES PATENT OFFICE

WILLIAM BARNETT, OF LOS ANGELES, CALIFORNIA

LAUNCHING DEVICE

Application filed November 30, 1929. Serial No. 410,737.

This invention appertains to a life-saving device and more particularly to novel means for launching a life-boat from the deck of a steam or like vessel.

It has, heretofore, been proposed of launching life and other boats from the side of a vessel by suitable davits but such appliances have not been successful in emergency cases in view of the fact that more than one person is required to lower the boat and the extreme danger from ropes swelling in wet weather so that they choke up the blocks and the freezing of the ropes in the blocks in cold weather causing the tipping of the boat and precipitating the passengers thereof into the water, and the danger of the boat being wrecked against the side of the ship.

It is therefore one of the primary objects of my invention to provide means for launching a life-boat from the deck of a steamer which will require only the service of one man and which will permit the effective launching of the boat from the deck of a vessel in a minimum amount of time.

Another object of my invention is to provide a novel launching device for a life-boat of the type shown in my pending application executed on even date herewith, the launching device consisting of inclined guideways for permitting the boat to dive into the water from off of the deck of a steam vessel.

A further object of my invention is the provision of a novel launching device for life-boats including inclined runways for the life boat whereby the boat will be slid off the deck of the vessel in an inclined position and with considerable speed so that the life-boat will dive into the water and away from the side of the vessel owing to the momentum thereof, and thus avoid the suction caused by the sinking of the steamer.

A further object of my invention is to provide a launching device for the life-boat from the deck of a steamer in which the life-boat is supported in a novel manner wherein the boat will be free to float from the deck of the steamer at all times should the steamer sink before time was had to properly launch the life boat.

A further important object of my inven-

tion is the provision of a life-boat launching device embodying inclined ways leading from the longitudinal center of the vessel toward the opposite sides thereof with a tilttable platform utilized for supporting the life-boat carried by the central portion of the ways with means for permitting the tilting of the platform toward one side of the vessel or the other, so that the life-boat will be permitted to slide off the platform and down the ways off of the deck of the vessel and into the water.

A further object of my invention is the provision of novel means for forming the platform and ways and the bottom of the life-boat so that the life-boat will be effectively guided during its passage off of the platform and ways, with anti-friction rollers for facilitating the easy and effective riding of the boat down the platform and ways.

With these and other objects in view, the invention consists in the novel construction, arrangement and formation of parts, as will be hereinafter more specifically described, claimed, and illustrated in the accompanying drawings, in which drawings:

Figure 1 is a fragmentary view of steam vessel in transverse section showing my improved boat and boat launching device incorporated therewith, the life-boat being held in its normal position against accidental displacement.

Figure 2 is a similar view showing the platform tilted and the life-boat sliding down the ways to be launched from the side of the vessel.

Figure 3 is a view similar to Figure 2 showing a slightly modified form of launching device for relatively wide ships.

Figure 4 is an enlarged side elevation of my launching device incorporated with a steamship, parts of the launching device being shown broken away and in section, the life-boat being held on the device against accidental movement.

Figure 5 is a top plan view of my improved device with the life-boat removed therefrom.

Figure 6 is a transverse section through the launching device and life boat taken on the line 6—6 of Figure 4.

Figure 7 is a fragmentary top plan view of one end of one inclined way of the launching device showing the modified form thereof for relatively wide ships, and

Figure 8 is a fragmentary side elevation of the modified form of the launching device for relatively wide ships.

Figure 9 is a view similar to Figure 1 illustrating the form of my invention for narrow ships.

Figure 10 is a transverse section taken substantially on the line 10—10 of Figure 9, and

Figure 11 is a fragmentary longitudinal section taken on the line 11—11 of Figure 10.

Referring to the drawings in detail, wherein similar reference characters designate corresponding parts throughout the several views, the letter A generally indicates my improved device for launching a life-boat B from the sides of a steamship C.

The steamship C will not be described in detail as the same is of the ordinary or any preferred type but it is to be noted that my launching device extends transversely of the top deck 10 thereof.

The life-boat B is of a particular type, and as stated, forms the subject matter of an independent application for patent executed on even date herewith and this life-boat will not be described in detail in this application but it is to be noted that the same is of a diving type and that the same is so constructed that the same can be either launched from one side of the ship or the other. This life-boat B, as shown in Figure 6 of the drawings, includes a hull 15 having a central depending hollow keel 16 and a substantially flat bottom 17. Welded or otherwise secured to the flat bottom 17 on opposite sides of the keel 16 are auxiliary keels 18 and 19 which keels form guides for the life-boat B during the launching thereof. It is to be noted that the side keels 18 and 19 are of T-beam construction with the leg flange depending from the bottom of the boat to form the guide.

My improved launching device A comprises the opposite extending downwardly inclined ways 20 and 21 and as stated these ways extend from the longitudinal center of the ship at the top deck thereof toward the sides of the ship. These ways 20 and 21 are constructed identically the same and can be formed from suitable timbers 22 which can be bolted or otherwise secured to the central stateroom cabins 11 of the ship C. The outer lower ends of these timbers 22 rest upon the deck of the ship and can be bolted or otherwise secured thereto. The meeting points of the timbers or metal slides are suitably bolted together and support upstanding central brackets 23, which brackets support above the ways 20 and 21 the transversely extending shaft 24. Rockably mounted on the shaft 24 is a central platform 25 which in-

cludes side timbers or supporting boards 26. This platform extends equi-distantly beyond the shaft 24 and inward of the side boards 26 of the platform are auxiliary side rocking platforms 27 and 28. Each of the side tilting platforms 27 and 28 include side timbers or boards 29 and the inner end of the boards 29 of the tilting platforms 27 and 28 are arranged in overlapping relation and are rockably mounted on the shaft 24. It is to be noted that the boards 29 of the tilting platforms are arranged in spaced parallel relation to the boards 26 of the central platform 25 and that the side boards 29 beyond the ends of the platforms are provided with lateral extensions 30, which form a substantial continuation of the side boards 26 of the central platform 25.

The lateral extensions 30 have their upper faces grooved as at 31 which grooves 31 align with the space between the side boards 29 of the tilting platforms 27 and 28 and the side boards 26 of the central platform 25. The upper faces of the lateral extensions 30 and the side boards 29 are preferably provided with anti-friction rollers 32, for a purpose, which will be later described.

The upper faces of the beams 22 of the inclined ways 20 and 21 beyond the tilting platforms 27 and 28 are provided with guide tracks 33, which guide tracks extend to the extreme lower ends of said inclined ways. These tracks can be of a substantially U-shape in cross section and in all events, are provided with longitudinally extending central grooves 34 which align with the grooves 31 in the tilting platforms. The upper faces of the tracks 33 on opposite sides of the grooves 34 are likewise provided with anti-friction rollers 35.

As clearly shown in Figures 5 and 6 of the drawings, the ends of the side boards 29 or rails of the tilting platforms 27 and 28 are connected together by transverse cross beams 36 which beams are provided with centrally disposed transverse V-shaped notches 37, for a purpose, which will be also later described.

The central tilting platform 25 is substantially balanced at all times, and the tilting platforms 27 and 28 are held in a raised horizontal position by the use of jacks 38 and 39 which extend from the deck 10 of the vessel to the transverse beam 36.

These jacks 38 and 39 can be of any preferred type, such as pneumatic jacks, screw jacks, or the like but in the present instance I have shown the jack of the rack and pinion type. I desire, however, that these jacks be so constructed that the same be quickly released by a single person so as to permit the tilting of the release side platform and this releasing means can be so arranged as to be operated from the life-boat, if desired.

Normally the life-boat B is placed on the

central platform 25 with its ends on the side or end platforms 27 and 28 and the boat is held against movement by said jacks 38 and 39. The depending V-shaped keel 16 rests in 5 the V-shaped notches 37 formed in the transverse beams 36 of the side or end platforms 27 and 28 while the side keels or guide flanges 18 and 19 of the boat B rest in the space between the side boards 26 of the tilting platforms 10 25 and the side boards 29 of the end platforms 27 and 28 and in the grooves 31 of said platforms. The anti-friction rollers 32 engaging the bottom of the hull of the life-boat B.

15 Should the steam vessel C be in danger of sinking the life-boat is filled with its designated passengers and crew and the doors thereof (not shown) are closed tight and all 20 of the passengers are strapped into their seats, as fully disclosed in the mentioned pending application.

If the life-boat is to be launched from the left hand side of the vessel, referring to Figures 1 to 4 inclusive, the shaft 38 can be released so as to permit the same to move downward, which will permit the rocking of the side platform 27 and the central platform 25. The lift-boat B will now ride down off of the central platform 25 and the end platform 27 30 onto the guide tracks 32 and then off of the side of the ship into the water. The life-boat B will ride easily down from the launching device due to the guide beams provided and the anti-friction rollers and the boat B 35 should gain considerable momentum during its sliding down the launching device so as to carry the same well away from the side of the ship when the same strikes the water.

In ships having a relatively wide beam the 40 guide tracks 33 can be modified as shown in Figures 3, 7 and 8 of the drawings. In this instance the guide tracks 33 are divided longitudinally to form stationary guide sections 50 and sliding guide sections 51 for extending over the sides of the ship C. The sliding sections 51 may carry guide bolts 52 which are slidably received in longitudinal slots 53 formed in the stationary guide sections 50.

It is obvious that the sliding sections 51 can 50 be easily extended and that the same will form an effective guide for the life-boat during its travel over the sides of the vessel.

In Figures 9 to 11 inclusive, I have shown 55 an arrangement of my invention for narrow ships and in this construction I provide the central tilting platform or cradle 60 pivoted at its transverse center on suitable brackets 51 carried by the meeting point of the downwardly and outwardly inclined guide timbers 62 which reach the sides of the ship. The brackets 61 on the shaft thereof also carry the side tilting platforms 63 and 64 which are of such a length, in this instance, as to 60 extend to the sides of the ship and to rest on the guide ways 62. Thus the necessity of pro-

viding the additional guide ways for the life boat carried by the supporting timbers is eliminated. The side or end tilting platforms 63 and 64 are normally held in a raised position by the jacks 65, which are of the same 70 construction and operated in the same manner as the jacks previously described.

As shown in Figures 9, 10 and 11, I can also provide guide plungers 66 and guide cylinders 57 for the side or end tilting platforms and the cylinders can be carried by the deck of the vessel. These plungers and cylinders are located on opposite sides of the jacks 65 and prevent any tendency of the 75 end platforms to shift laterally during the lurching of the vessel. Further these plungers and pistons can act in the nature of shock absorbers to reduce the too rapid descent of the end platforms when the jacks are released.

80 From the foregoing description, it can be seen that I have provided an exceptionally simple and efficient launching device for life-boats.

85 Changes in details may be made without departing from the spirit or the scope of this invention, but:—

What I claim as new is:—

1. A launching device for boats, comprising an inclined way, a centrally disposed tilting cradle rockably mounted intermediate its ends on said way, an auxiliary end cradle rockably mounted on said way and forming an extension of the central rocking platform, and releasable jacks engaging the end 100 platform for normally holding the same in a horizontal position.

2. The combination with a boat launching device including an inclined way, a tilting platform rockably mounted at the upper end of the way, an extension and tilting platform forming an extension of the central platform rockably mounted at the upper end of said way, guide tracks carried by the inclined way, and the tilting and end platforms, a boat received on the central and end platforms, and guide ribs carried by the bottom of the boat for engaging said guide tracks.

3. The combination with a vessel, of a life-boat launching device carried by the deck of the vessel including oppositely extending inclined ways, a central platform rockably mounted intermediate its ends at the upper ends of said ways, tilting end platforms rockably carried by the upper ends of the inclined ways, and extending beyond the central platform and over the inclined ways, said central platform and end platform being adapted to receive the boat to be launched, the inclined ways extending to the edges of the vessel, and releasable jacks engaging the tilting end platforms adjacent to the outer terminals thereof.

4. The combination with a vessel, of a life-

boat launching device carried by the deck of the vessel including oppositely extending inclined ways, a central platform rockably mounted intermediate its ends at the upper 5 ends of said ways, tilting end platforms rockably carried by the upper ends of the inclined ways, and extending beyond the central platform and over the inclined ways, said central platform and end platform being adapted 10 to receive the boat to be launched, the inclined ways extending to the edges of the vessel, and releasable jacks engaging the tilting end platforms adjacent to the outer terminals thereof, and extension tracks carried 15 by the outer terminals of the inclined ways for extending beyond the sides of the vessel.

5. The combination with a vessel, of a launching device for life-boats comprising oppositely extending inclined ways leading 20 from the longitudinal center of the vessel to the sides thereof, brackets carried by the upper ends of the inclined ways, a supporting shaft carried by the brackets and extending transversely of the inclined ways, a central 25 rocking platform rockably mounted on the shaft intermediate its ends, end platforms rockably mounted on the shaft and extending beyond the ends of the central platform, guide tracks on the inclined ways beyond the 30 outer terminals of the end tilting platforms, and releasable jacks engaging the end platforms adjacent to the opposite ends thereof for normally holding the same in a horizontal plane.

35 6. The combination with a vessel, of a launching device for life-boats comprising oppositely extending inclined ways leading from the longitudinal center of the vessel to the sides thereof, brackets carried by the upper 40 ends of the inclined ways, a supporting shaft carried by the brackets and extending transversely of the inclined ways, a central rocking platform rockably mounted on the shaft intermediate its ends, end platforms 45 rockably mounted on the shaft and extending beyond the ends of the central platform, guide tracks on the inclined ways beyond the outer terminals of the end tilting platforms, releasable jacks engaging the end platforms adjacent to the opposite ends thereof 50 for normally holding the same in a horizontal plane, and extension tracks slidably carried by the first mentioned track for extending beyond the deck of the vessel.

55 7. A launching device for boats, comprising an inclined way, a boat supporting tilting cradle rockably mounted upon said inclined way, an auxiliary end cradle forming an extension of said tilting cradle and constituting a continuation of the tilting cradle 60 when the same is tilted, for launching a boat from said inclined way.

8. A launching device for boats comprising an inclined way, a tilting cradle rockably 65 mounted above said inclined way, an auxil-

70 iary end cradle constituting an extension for said tilting cradle when the tilting cradle is extended, and releasable means engaging the auxiliary cradle for normally holding the auxiliary cradle in a horizontal position.

In testimony whereof I affix my signature.

WILLIAM BARNETT.
